(57) **CLAIM**

The ornamental design for a food tray as shown and described.

DESCRIPTION

FIG. 1 is an isometric bottom view of a food tray.

FIG. 2 is an isometric top view of the food tray.

FIG. 3 is a bottom view of the food tray.

FIG. 4 is a top view of the food tray.

FIG. 5 is a front side view of the food tray.

FIG. 6 is a back side view of the food tray.

FIG. 7 is a right side view of the food tray; and,

FIG. 8 is a left side view of the food tray.

The broken lines in the drawings show portions of the food tray, which form no part of the claimed design.

1 Claim, 8 Drawing Sheets
